EYE SURGICAL TOOL

Ely Jay Crary, 4730 Austell Road,
Austell, Ga. 30001

Filed Oct. 1, 1970, Ser. No. 25,287

Term of patent 14 years

Int. Cl. D24—03

U.S. Cl. D83—12

FIG. 1

FIG. 2

FIG. 5

FIG. 3

FIG. 1 is a side perspective view of the eye surgical tool.

FIG. 2 is a side elevational view of the eye surgical tool, showing the side opposite from the side shown in FIG. 1.

FIG. 3 is an end view of the eye surgical tool.

FIG. 4 is an end view of the eye surgical tool, showing the end opposite from the end shown in FIG. 3.

FIG. 5 is a side perspective view of a modified form of the eye surgical tool, with the tool of FIG. 5 being similar to the tool of FIGS. 1—4 except for the shape of the handle portion.

I claim:

The ornamental design for an eye surgical tool, substantially as shown and described.
